PUMP

Donald G. Miller, Reno, Nev.

Application July 27, 1945, Serial No. 607,404

5 Claims. (Cl. 103—37)

1

This invention relates to a pump and particularly to a high-pressure pump, it being one object of the invention to provide a pump so constructed that when it is in operation pressure may be maintained at a constant degree and thereby cause fluid discharge from the pump to be subjected to a constant pressure during operation of the pump.

Another object of the invention is to provide a pump having a piston slidably mounted in a cylinder for reciprocating movement therein, the cylinder being shiftable longitudinally and yieldably held against movement in one direction so that during operation of the pump the piston may exert predetermined pressure upon liquid in the cylinder and, if pressure exerted increases beyond a predetermined point, the cylinder moves longitudinally with the piston and thus prevent excessive pressure from being applied to the liquid discharge from the cylinder.

Another object of the invention is to so mount the cylinder that adjustments may be made to regulate the amount of pressure which may be exerted by the piston before the cylinder moves with the piston to prevent excessive pressure being applied to the liquid.

Another object of the invention is to provide a pump so constructed that it maintains the same pressure at any speed as long as the capacity is large enough.

Another object of the invention is to so construct the pump that it will maintain the predetermined pressure and at the same time does not pull on the source of power due to the fact that its spring pushes in favor of the power during half the revolution of the drive shaft.

Another object of the invention is to provide a pressure-controlled pump which is simple in construction, easily adjusted for predetermined pressure, and not liable to get out of order when in use. The invention is illustrated in the accompanying drawings, wherein:

Figure 1 is a sectional view taken longitudinally through the improved pump.

Figure 2 is a sectional view taken along the line 2—2 of Figure 1.

Figure 3 is a sectional view upon an enlarged scale taken along the line 3—3 of Figure 1, and

Figure 4 is a view looking at one end of the pump.

This improved pump has a cylinder 1 formed with a longitudinally extending bore or chamber 2 and having thick walls so that it may withstand high pressure. The cylinder 1 is disposed horizontally and slidably mounted through an opening 3 formed in a standard 4 rising from a base 5. At its front end the cylinder is externally thickened to form a collar 6 for limiting sliding movement of the cylinder in one direction and through this end portion of the cylinder

2

are formed radially extending ports 7 and 8 constituting an inlet and an outlet for the pump. Check valves 9 and 10 are mounted in outer end portions of the ports 7 and 8, the valve 9 being an inwardly opening valve and the valve 10 an outwardly opening valve. These valves not only serve for controlling flow of fluid into and out of the chamber 2 of the pump, but also constitute nipples to which pipes may be connected by flexible connections for leading liquid to and from the pump.

A piston 11 is slidably received in the chamber 2 and in order to prevent leakage, the rear end of the cylinder has been provided with a packing gland 12 by means of which packing 13 is compressed tightly about the piston. The rear end of the piston is pivoted to a pitman 14 by a pin 15 and at its rear end the pitman is formed with a sleeve or collar 16 which is circular in shape and fits about a circular cam-block 17 carried by a drive shaft 18. The drive shaft is rotatably mounted through standard 19 carried by base 5 and rotary motion may be imparted to the shaft by a belt trained about a pulley 20 or in any other desired manner. During rotation of the drive shaft, reciprocating movement is imparted to the piston and as this piston reciprocates in the cylinder, liquid is drawn inwardly through the intake port 7 and expelled through the outlet port 8. As pressure exerted by the piston increases during forward movement of the piston in a power stroke, it is desired to prevent this pressure from increasing beyond a predetermined point. Therefore, the cylinder has been slidably mounted through the standard 4. A shaft or plunger 21 extends forwardly from the front end of the cylinder and slidably passes through a sleeve 22 which is slidably mounted through an opening 23 formed horizontally through a standard 24 carried by the base. This sleeve serves as an adjustable abutment for one end of a helical spring 25 coiled about the plunger 21 and having its rear end bearing against the front end of the cylinder, and when pressure exerted by the forwardly moving piston reaches a predetermined point, additional pressure will cause action of the spring 25 to be overcome and the cylinder will move forwardly with the piston. Therefore, the pressure may only be built up to a predetermined degree in the chamber 2. At its front end the sleeve 22 fits into an opening 26 formed through a lever 27 which is disposed vertically and has its lower end pivotally mounted between the ears 28 of a bracket 29 by a pin or shaft 30. The sleeve is held in the opening 26 by screws 31 which are threaded through the lever from opposite side edges thereof and have their inner ends engaged in an annular groove 32 formed about the sleeve and from an inspection of Figure 1 it will be readily understood that when

the lever is swung longitudinally of the base 5, tension of the spring 25 may be regulated so that the cylinder 1 will be prevented from moving longitudinally in a forward direction until pressure within the chamber 2 is increased to such an extent that action of the spring is overcome. The bracket 29 is formed at its front end with an upstanding head board 33 having a threaded opening formed near its upper end and through this opening passes an adjusting screw 34. The inner or rear end of screw 34 has an abutting engagement with lever 27 and by adjusting this screw the lever may be prevented from swinging forwardly beyond a position in which predetermined tension will be applied to the spring. By turning the screw in a loosening direction, the lever may be permitted to move toward the position indicated by dotted lines in Figure 1 to decrease tension upon the spring and allow movement of the cylinder with the piston at a lower pressure and by turning the screw in a tightening direction the lever may be swung toward standard 24 and thus increase tension upon the spring. The pump may therefore be accurately set for any predetermined pressure.

It is thought that persons skilled in the art to which the invention relates will be able to obtain a clear understanding of the invention after considering the description in connection with the drawings. Therefore, a more lengthy description is regarded as unnecessary.

Minor changes in the shape, size and arrangement of details coming within the field of invention claimed may be resorted to in actual practice, if desired.

Having thus described the invention, what is claimed is:

1. A pressure-controlled pump comprising a cylinder mounted for sliding movement, means on the ends of said cylinder for limiting its endwise movement, a piston mounted for reciprocating movement in said cylinder, said piston being retained in said cylinder at all times, spring means yieldably resisting movement of the cylinder during movement of the piston in a power stroke, and pivoted means for regulating tension of said spring and allowing movement of the cylinder with the piston when pressure exerted by the piston exceeds a predetermined degree.

2. A pressure-regulated pump comprising a support, a cylinder slideable longitudinally through said support, a piston mounted for reciprocating movement in said cylinder, said piston being retained in said cylinder at all times, a bar extending from said cylinder, a second support, a sleeve shiftable longitudinally through the second support and slidably receiving said bar, a spring about said bar between said sleeve and said cylinder yieldably resisting movement of the cylinder during a power stroke of the piston, and pivoted means for shifting said sleeve longitudinally to adjusted position for placing the spring under predetermined tension.

3. A pressure-regulated pump comprising a base, a support carried by said base, a cylinder slideable longitudinally through said support, a reciprocating piston operating in said cylinder, a second support carried by said base and formed with an opening, a sleeve shiftable longitudinally through the second support, a bar extending from said cylinder and slidably engaged in said sleeve, a spring about said bar between the cylinder and the confronting end of said sleeve, a

mounting carried by said base, a lever pivoted to said mounting and pivotally connected with said sleeve, and a set-screw carried by said mounting and engaging said lever to limit movement of the lever away from the second support and place said spring under predetermined tension.

4. A pressure-regulated pump comprising a base, a support extending upwardly from said base, a cylinder slideable longitudinally through said support, a piston mounted for reciprocating movement in said cylinder through the rear end thereof, bearings carried by said base, a drive shaft rotatably carried by said bearings, a cam disc carried by said drive shaft, a pitman about said cam disc pivoted to the rear end of said piston for reciprocating the piston during rotation of the drive shaft, a second support carried by said base forwardly of the first support, a sleeve slideable through the second support, a bar extending forwardly from the front end of said cylinder and slidably received in said sleeve, a spring about said bar having its ends in abutting engagement with the front end of the cylinder and the rear end of the sleeve, a mounting bracket carried by said base forwardly of the second support and having ears spaced transversely from each other and a head board extending upwardly above its ears, a lever pivotally mounted at its lower end between said ears and having its upper portion formed with an opening into which the forward end of said sleeve extends, screws passing through said lever from opposite side faces thereof with their inner ends engaging in a circumferentially extending seat adjacent the front end of said sleeve, and a set-screw threaded through the head board with its inner end abutting said lever to limit forward movement of the lever and apply predetermined tension to said spring.

5. A pressure-regulated pump comprising a base, a support extending upwardly from said base, a cylinder slideable through said support in a direction longitudinally of the base, a piston mounted for reciprocating movement in the cylinder through the rear end thereof, drive means carried by said base and connected with the rear end of said piston, a second support carried by said base forwardly of the first support, a bar extending forwardly from the front end of said cylinder, a sleeve slideable through said second support in a direction longitudinally of the base and slidably receiving said bar, a spring about said bar between the front end of the cylinder and the rear end of said sleeve, a mounting carried by said base forwardly of the second support, a lever disposed vertically with its lower end pivoted to said mounting and having its upper portion pivotally connected with the forward end of said sleeve and an abutment adjustably carried by said mounting for engagement by said lever to limit forward movement of the lever and control tension of the spring.
